John V. Joslyn, New York, N.Y. (6 John St., Sag
Harbor, Long Island, N.Y.)

Filed Oct. 25, 1962, Ser. No. 233,044

3 Claims. (Cl. 273—97)

This invention relates to an amusement game and more particularly to a game wherein a ball is transmitted between two players much the same as in a tennis match.

The object of the invention is to provide a game, sturdily constructed and economical to produce, for the amusement of its participants.

Yet another object of this invention is to provide a competitive activity for children and adults wherein a score may be kept and a winner thereby be determined.

A further object of this invention is to provide an amusement toy which may be manipulated by either the participants' hands or feet.

The aforesaid objects of the present invention, and other objects which will become apparent as the description proceeds, are achieved by providing a frame on which is pivotably mounted a lever means. One end of the lever means is pivotably connected to the frame while the other end has a resilient means attached thereto. A first striking means is connected to one end of the frame for striking the resilient means and a second striking means is attached to the other end of the frame for striking the resilient means, the resilient means being movable between the first and second striking means. A stop means is disposed on the frame for stopping the lever means out of reach of the first and second striking means.

For a better understanding of the present invention reference should be had to the accompanying drawings, wherein like numerals of reference indicate similar parts throughout the several views wherein:

FIGURE 1 is a side view of the invention, and

FIGURE 2 is a top view of the invention.

With specific reference to the form of the present invention illustrated in the drawings, and referring particularly to FIGURE 1 the frame of the game is generally indicated by the reference numeral 10.

The frame 10 is made of aluminum tubing, however other light and workable material may be used in its place. Connected to the center of the frame 10 is a metal bracket 12 which serves as a place for pivotably mounting a lever means or lever arm 14. The lever means or lever arm 14 in this instance is a flexible one quarter inch tube, however other, somewhat flexible material may be used in its place.

Disposed on one end or the free end 16 of the lever arm 14 is a resilient means or resilient ball 18. The resilient ball 18 is made of polyethylene but other resilient material, such as rubber, may be used. The other end 20 of the lever arm 14 is connected to the bracket 12 such that the lever arm 14 may pivot about its point of connection 22. The resilient ball 18 therefore is movable in an arc 23 (FIGURE 1) between the ends of the frame.

In order to keep the lever arm 14 pivoting about its point of connection 22 and the resilient ball 18 moving in an arc 23 a first striking means or first paddle 24 is provided at one end 26 of the frame 10. The frame 10 is curled back on itself forming a U-shaped bracket 28 on which the first striking means or paddle 24 may be mounted. As seen in FIGURE 2 the first striking means 24 is in the form of a paddle, however it should be understood that the first striking means may take other forms such as a rectangle, oval or the like.

The first paddle 24 is pivotably mounted on the bracket 28 by means of a stamped bracket 30 and pin 32. The

2

first paddle 24 is pivotable in an arc 33 in the same plane as the arc 23 struck by the lever arm 14 and the resilient ball 18.

In order to provide a means for moving the resilient ball 18 in the arc 23 back and forth between the ends of the frame 10, much as in a tennis match, the other end 34 of the frame 10 is curled back on itself forming a U-shaped bracket 36. A second striking means or second paddle 38 is pivotably mounted on the bracket 36 by means of a stamped bracket 40 and pin 42. The second paddle 38 is seen to move in an arc 43 (FIGURE 1).

Structurally, the bracket 12, to which is connected the lever arm 14, is provided with projections 44 and 46. The projection 44 is on the side of the frame 10 facing the first paddle 24 and it may be seen that it acts as a stop means so that the movement of the lever arm 14 is limited or restricted and in this position the resilient ball 18 could not be struck by the first paddle 24. However, the lever arm 14 is made of a flexible material and if the lever arm 14 when following the arc 23 strikes the stop 44 the lever arm is flexed somewhat and the resilient ball 18 is now within the reach of the first paddle 24 and may be struck thereby and sent toward the other end 34 of the frame 10. The exact same relationship as heretofore described holds true for the relationship of the stop 46 and the second paddle 38. When the lever arm 14 is in the flexed position the resilient ball 18 is within reach of the second paddle 38 so that the resilient ball 18 may be struck and sent in the arc 23 toward the first paddle 24 so that it in turn may be struck and returned much as in a tennis match.

The stamped metal brackets 30 and 40 are provided with horizontally extending portions 48 and 50, as seen in FIGURE 2, so that the frame 10 may be placed in an upright position on the floor or a table. It should be noted that the first and second paddles 24 and 38 may be manipulated by the participants' hands or feet and therefore the frame 10 should be placed in an appropriate position so that the paddles 24 and 38 may be comfortably manipulated.

Operation

The game is started by throwing the resilient ball 18 into action such that the lever arm 14 and resilient ball 18 move in a path described by arc 23. The lever arm 14 in its descent initially will contact one of the stops 44 or 46, by way of illustration assume that the lever arm 14 contacts stop 44. If the lever arm 14 were rigid the resilient ball 18 would be out of the reach of the first paddle 24 as seen in FIGURE 1. However, the lever arm 14 is made of a flexible material so that the momentum of the lever arm 14 and resilient ball 18 causes the lever arm 14 to bend or flex when it contacts stop 44 thus bringing the resilient ball within the reach of the first paddle 24. The first paddle 24 when pivoted at the proper instant causes the first paddle 24 to strike the resilient ball 18 thereby causing it to move in the path described by the arc 23 toward the other end 34 of the frame 10. The lever arm 14 when contacting the stop 46 is caused to flex so that the resilient ball 18 may be struck by the pivoting second paddle 38 and returned toward the first paddle 24.

This operation is repeated until one of the participants mistakes his manipulation of the paddle and the resilient ball 18 is not returned toward his opponent. It may readily be seen that if the player fails to strike the resilient ball 18 with his paddle during the proper instant of overshoot or the flexing of the lever arm 14 he will not be able to return the resilient ball 18 toward his opponent. This scores a point for the erring player's opponent. Scores may be kept, as in a tennis match or table tennis game, so that a winner may be determined.

While in accordance with the patent statute a preferred embodiment of the present invention has been described in detail, it is to be particularly understood that the invention is not limited thereto or thereby.

We claim:

1. A game comprising a frame, flexible lever means disposed on said frame, one end of said flexible lever means being pivotably mounted on said frame, resilient means connected to the free end of said flexible lever means for receiving blows, a first striking means pivotably mounted on one end of said frame for striking said resilient means, a second striking means pivotably mounted on the other end of said frame for striking said resilient means, said resilient means being movable between said first and second pivotably mounted striking means, and stop means disposed on said frame for stopping said flexible lever means thereby keeping said resilient means out of reach of said first and second pivotably mounted striking means, said flexible lever means having a degree of flexibility rendering it capable of flexing about said stop means such that the free end of said flexible lever means is brought within range of said pivotably mounted first or second striking means, thereby allowing said resilient means to receive a blow.

2. A game comprising a frame, a lever means disposed in the center of said frame, one end of said lever means being pivotably mounted on said frame, resilient means connected to the free end of said lever means for receiving blows, said lever means being flexible, a first striking means pivotably mounted on one end of said frame for striking said resilient means, a second striking means pivotably mounted on the other end of said frame for striking said resilient means, said resilient means being movable in an arc between said first and second pivotably mounted striking means, and stop means disposed on

35

said frame for stopping said flexible lever means thereby keeping said resilient means out of reach of said first and second pivotably mounted striking means, said flexible lever means having a degree of flexibility such that when said flexible lever means strikes said stop means said flexible lever means will bend allowing its free end to come within range of said first or second pivotably mounted striking means so that the resilient means may be struck.

5 3. A ball game comprising a frame, a flexible lever arm disposed in the center of said frame, one end of said flexible lever arm being pivotably mounted to said frame, a resilient ball connected to the free end of said flexible lever arm for receiving blows, a first paddle pivotably mounted on one end of said frame for striking said resilient ball, a second paddle pivotably mounted to the other end of said frame for striking said resilient ball, said resilient ball being movable in an arc between said first and second paddles, and stop means disposed on said frame for stopping said flexible lever arm thereby keeping said resilient ball out of reach of said pivotably mounted first and second paddles, said flexible lever arm having a degree of flexibility such that when said flexible lever arm strikes said stop means said flexible lever arm will bend allowing its free end to come within range of said pivotably mounted first or second paddle so that the resilient ball may be struck and thereby served and returned between said paddles.
